Primary Examiner — Janice Hallmark*(74) Attorney, Agent, or Firm* — McGarry Bair PC**CLAIM**

The ornamental design for a ceiling fan light kit, as shown and described.

DESCRIPTION

FIG. 1 is a top perspective view of a ceiling fan light kit shown in the environment of a ceiling fan, showing my new design;

FIG. 2 is a bottom perspective view thereof, with the ceiling fan environment removed;

FIG. 3 is a top view thereof;

FIG. 4 is a bottom view thereof; and,

FIG. 5 is a side view thereof.

Portions of the ceiling fan light kit and ceiling fan environment shown in broken lines form no part of the claimed design. Unshaded portions of the ceiling fan light kit located between solid line and broken line subject matter form no part of the claimed design.
